UNITED STATES PATENT OFFICE

156,503

CAKE TURNER

Paul Grancell, Los Angeles, Calif.

Application August 25, 1947, Serial No. 141,054

Term of patent 3½ years

(Cl. D44—29)

To all whom it may concern:

Be it known that I, Paul Grancell, a citizen of the United States, and a resident of Los Angeles, California, have invented a new, original, and ornamental Design for a Cake Turner, of which the following is a specification, reference being had to the accompanying drawing, forming part thereof.

Referring to the drawing:

Figure 1 is a top plan view of a cake turner showing my new design;

Figure 2 is a side elevational view thereof;

Figure 3 is an elevational view of the other side; and

Figure 4 is a bottom plan view.

I claim:

The ornamental design for a cake turner, as shown.

PAUL GRANCELL.
